UNITED STATES PATENT OFFICE.

CARL H. RANKIN, OF WELLSBURG, WEST VIRGINIA, ASSIGNOR, BY MESNE ASSIGNMENTS, OF ONE-FOURTH TO CHARLES JAMES PURDIE PRATT, OF LONDON, ENGLAND.

AUTOMATIC DISCHARGE VALVE.

Application filed December 6, 1919. Serial No. 342,887.

In my pending application on feeding mechanisms, Serial No. 323,351, filed September 13, 1919, there is disclosed means for intermittently feeding lumps or charges of molten material such as glass from a heating tank or the like, the feeding being effected under pressure applied by means of a reciprocating plunger working above an outlet nozzle or opening in the mouth of the tank.

The present invention is an improved automatic discharge valve or mechanism capable of use on a machine of the type disclosed in said application.

15 The objects of the present invention are to generally improve the discharging members and also produce a better operation, and will be more fully apparent from the description which follows.

20 In the accompanying drawings Fig. 1 is a vertical section of the discharge valve or mechanism, in closed position. Fig. 2 is a similar partial view with the parts in open position. Figs. 3 and 4 are details in plan 25 and elevation of one of the valve members. Fig. 5 is a section on the line 5—5 of Fig. 1.

Referring specifically to the drawings, A indicates the neck of a glass tank or the like which contains the molten material indicated at B, and is provided with an outlet mouth or opening C from which the material is discharged into molds or the like, in the same manner as described in my pending application. These necks are commonly found on glass tanks, and need no extended description. Some kind of cutoff mechanism will be associated with these parts, such for example as the cutoff devices disclosed in my said application, although the 30 particular form of said mechanism is not material to the present invention, which relates to the means for controlling the flow or feed of the metal from the neck. A frame X with a cross-piece Y hinged at 35 thereto, supports the parts to be described, said frame extending above the neck.

40 8 is a plunger, and 7 is a cylinder surrounding the same. These parts depend through an opening in the top of the neck, and are made of refractory material. The lower end of the plunger 8 works toward and from a tapered throat 11 which leads to the mouth C, and the cylinder 7 works to and from a seat or surface 10 at the top 45 of said throat. The plunger 8 is connected

by a rod 5 to a piston C² which works in a cylinder B², and this cylinder is supplied at one end with compressed air through a pipe A² and at the other end through a pipe D², whereby the piston and plunger may be 50 raised or lowered.

The cylinder 7 is connected by rods 4 to 6 to pistons C¹ and C³ which work in cylinders B¹ and B³ to one end of which air is admitted through pipes A¹ and A³ and to 65 the other end through pipes D¹ and D³, whereby the pistons and the cylinder 7 are raised or lowered. One piston and cylinder would perhaps be enough for the purpose but two are considered to be better. The 70 flow of compressed air to the respective ends of the cylinders may be controlled by any suitable mechanism, such for example as the valve actuating mechanism disclosed in my pending application Serial No. 323,946, 75 filed September 15, 1919, the purpose being to reciprocate the plunger and the cylinder up and down at proper times according to the operation of the charging mechanism as a whole. The cylinders are supported upon 80 the cross-bar Y, and to vary the length of the stroke of each piston, each cylinder is provided with a movable head indicated respectively at E¹, E² and E³ which may be adjusted up and down by screw stems S, 85 which heads act as stops for the movement of the piston, the pipes A¹, A² and A³ communicating with bores extending through said heads. The cylinder 7 is provided with holes 9 through the same which admit hot 90 gases from the space in the upper part of the neck above the glass or other material to the space between the cylinder 7 and the piston 8. This is of some importance as it keeps the parts at a uniform temperature 95 to that of the molten glass and prevents chilling of the latter within the cylinder.

As described in my said application No. 323,351, the present devices will discharge a predetermined amount of molten material 100 in the form of a lump, at each operation. The amount is determined by the length of stroke of members 7 and 8. In operation, when compressed air is admitted to the bottom of the cylinders B¹ and B³ it lifts the 105 cylinder 7 from the seat 10, and at or about the same time the plunger 8 is lifted by admitting air to the bottom of the cylinder B², and the molten material flows in under the cylinder and plunger as indicated in Fig. 110

2. Then the cylinder 7 is forced down to its seat, cutting off the flow from the neck to the outlet, and this is followed by the depression of the plunger 8 as shown in Fig. 1, forcing out a lump or charge of glass through the mouth C. These operations are repeated in proper time as will be understood.

One advantage of the cylinder 7 is that it acts to prevent flow of impurities from the top surface of the metal into the discharge outlet. It is known that most impurities float on the top surface of the metal, and by means of this cylinder the charges are drawn from the bottom of the neck, the impurities being cut off, since the cylinder never rises above said surface. Another advantage exists with respect to replacement or repair. If the plunger 8 is to be replaced, as it must be from time to time, the cylinder 7 is lowered to closed position, which cuts off the flow, and the plunger 8 can then be withdrawn or lifted out without disturbing said cylinder. Or if the cylinder is to be replaced, the plunger 8 can be lowered sufficiently to close the outlet, and then the cylinder 7 can be lifted out and a new cylinder inserted. This is important, because the valve members can be changed without discharging or chilling the molten material in the tank.

The changes referred to are conveniently effected by the hinging of the cross bar Y at 12. Thus the rods 4, 5 and 6 can be disconnected from the cylinder 7 and piston 8 and the bar Y and the cylinders, etc. carried thereby can be swung around on the hinge 12 out of the way, so that said cylinder or piston can be changed or removed as desired.

The operation of the discharging mechanism, briefly referred to above, may be further elucidated as follows, since it forms in effect a new method of discharging or feeding a predetermined quota or charge of molten glass at each operation.

It will be noted that the cylinder 7 is open at the top to the atmosphere, and consequently when the cylinder drops to closed position, as shown in Fig. 1, it segregates or cuts off a quota or charge therein, and also relieves the charge of the pressure of the glass in the tank. The surface of the quota is then subjected only to atmospheric pressure, and the flow through the orifice C is consequently a gravity flow accelerated by the manipulation of the rod-like member or plunger 8, the action of which is somewhat analogous to the action of a puntyn with a charge of glass mounted on or adhering to the end thereof. Inasmuch as the upper surface of the segregated quota is not confined the member 8 does not increase the pressure to which this quota is subjected except by entering the quota and displacing

a portion thereof and thereby increasing the head of the quota itself, by causing a relative rise thereof in the cylinder 7. The delivery of the segregated quota is thereby controlled by the manipulation of the plunger 8 rather than by a direct forcing action such as would occur by the descent of a plunger of the same diameter as the interior of the cylinder 7. The downward movement of the plunger occasions a downward movement of the quota due to a mechanical entrainment which is accentuated by the cohesion and adhesion of the glass, so that a downward movement of the plunger accelerates the flow through the orifice, and this acceleration may be modified by varying the extent and speed of movement of the member 8. Also upward movement of the plunger will act to retard or check the flow through the orifice. This control is accomplished by manipulation of the member 8, and the pressure on the charge is not materially varied, and the discharge is more effective and is subjected to better control because the charge is relieved of the head or pressure of the glass within the tank, the gravity head of the charge itself being relatively small and not sufficient to offset or resist the entraining action of the plunger.

The surface of the segregated quota follows the movement of the member 8, as illustrated in Figs. 1 and 2. As the plunger moves down, the surface assumes the shape indicated in Fig. 1, that is somewhat concave, and when the plunger moves up the surface assumes a convex shape as shown in Fig. 2. The surface or skin tension of the glass contributes to this action, and consequently the surface acts somewhat like a diaphragm, assisting the plunger in moving glass through the orifice when it descends, and in causing a reverse flow or stop when the plunger ascends. The proper control of the plunger thereof accelerates or retards the flow of the quota or charge from the orifice without varying the fluid pressure to which the charge is subjected. Adhering and cohering characteristics of molten glass make it possible for a rod or puntyn-like member, such as 8, to produce the desired result, as distinguished from a forcible ejection such as would be produced by a piston giving a positive pressure ejection.

In this connection it may be explained that in glass machines it is impossible to work successfully with close clearances for the purpose of controlling flow of molten glass, whereby a rod spaced from a cylinder is superior in its action to a close fitting piston, and the action of the rod may be controlled to govern the size and shape of the delivered charge. In a glass machine, the advantages of dropping a charge as a complete drop, or with a reduced neck as

shown in Fig. 1 are well understood as compared with a solid stream of stalactite form, since the latter causes a large shear mark. This desirable result is accomplished

- 5 by control of the rod 8 by fluid pressure in connection with the diaphragm-like action, above referred to, and is comparable to the dropping action of a punty in the hands of a workman, and is not possible
 10 with a piston working with a close clearance, as has been suggested in the prior art. Reference has already been made, above, to the fact that the amount of the charge or segregated quota can be varied by variation in
 15 the length of stroke of the members 7 and 8.

I claim:-

1. The combination with a tank for molten material, having a discharge outlet and a seat around said outlet, of a plunger movable in the tank toward and from said outlet, to eject material therefrom, and a tubular cut-off member surrounding said plunger and movable to and from said seat, said cut-off member having an opening above the

- 20 level of material in the tank to admit gases to the space between the plunger and said member.
 25 2. The combination with a tank for molten material, having a discharge outlet, of a plunger movable in the tank, toward and from said outlet, a reciprocating cut-off member surrounding said plunger, fluid pressure cylinders provided with piston connected to said plunger and member respectively, and means to vary the stroke of the pistons.

- 30 3. The combination with a tank for molten material, having a discharge outlet, of a plunger movable in the tank, toward and from said outlet, a reciprocating cut-off member surrounding said plunger, fluid pressure cylinders provided with pistons connected to said plunger and member respectively, and means to vary the stroke of the pistons, said means comprising adjustable heads in the cylinders, to stop the movement of the pistons at desired points.

- 35 4. The combination with a tank for molten material, having a discharge outlet, of a plunger movable in the tank to and from said outlet, to eject material therefrom, said plunger being movable to contact with the wall around said outlet to close the same, and a cut-off member surrounding and spaced from said plunger and movable to and from said outlet and adapted to close said outlet when moved to contact with the wall surrounding same.

- 40 5. The combination with the neck of a tank for molten material, said neck having a discharge mouth in the bottom thereof, of a plunger working through the top of the neck to and from said mouth and adapted to close same, and a tubular cut-off member surrounding and spaced from said plunger

and working through the top of the neck, to and from contact with the bottom of neck around said mouth.

6. In combination with a receptacle for molten glass having a delivery orifice formed in the bottom thereof, a plunger located above and reciprocable toward and away from said orifice, a sleeve surrounding said plunger and movable to different positions with relation to said orifice, and means for periodically reciprocating said plunger.

7. In combination with a receptacle for molten glass having a submerged delivery orifice formed therein, a plunger projecting into the glass contained within said receptacle and reciprocable toward and away from said orifice, a sleeve surrounding said plunger and movable toward and away from said orifice, means for periodically reciprocating said plunger and means for moving said sleeve.

8. In combination with a receptacle for molten glass having a submerged flow orifice therein, a reciprocable plunger movable toward and away from said orifice, a reciprocable sleeve surrounding the orifice end of said plunger and movable toward and away from said orifice, and means for reciprocating both said plunger and said sleeve.

9. In combination with a receptacle adapted to contain a body of molten glass, and having a flow orifice formed therein, a movable sleeve extending into the body of glass contained in the receptacle for accumulating a quota of glass from said body, a plunger extending freely through said sleeve and into said quota and means for moving said plunger so that the end thereof beyond said sleeve moves into and out of said orifice.

10. In combination with a receptacle adapted to contain a body of molten glass and having a flow orifice formed in the bottom thereof, a sleeve extending downwardly through said body and in substantial alignment with said orifice, a plunger extending freely through said sleeve, and means for periodically reciprocating said plunger to periodically move the lower end thereof beyond the confines of said sleeve.

11. In combination with a receptacle adapted to contain a body of molten glass, and having a flow orifice formed therein, a sleeve projecting into said receptacle and extending into said body in proximity to said orifice, a reciprocal plunger extending freely through said sleeve, and means for periodically moving the free end of the plunger into said orifice.

12. The method of delivering a charge of molten glass from a receptacle provided with a flow orifice, which consists in segregating a quota of glass from the body and within the receptacle, relieving the segregated quota of the pressure of the body of glass, and causing the mold charged, formed from

- said quota, to assume the desired shape by moving a punty-like member towards and away from the flow orifice while the same is attached to the quota.
13. The method of delivering mold charges, which consists in segregating a quota of molten glass from a batch of such glass retained above the flow orifice, and in simultaneously reducing the pressure on the quota, then in causing the mold charge delivered from the quota to assume the desired shape upon issuing through the orifice by moving a punty-like member towards and away from the orifice while attached to the quota.
14. The method of delivering mold charges from a receptacle containing a body of molten glass and provided with a submerged orifice, which consists in segregating a quota of glass from the body immediately above the orifice, and in simultaneously reducing the pressure on the quota to retard the flow through the orifice, then in causing the charge delivered from the quota through the orifice to assume the desired shape by moving a punty-like member extending into the quota, towards and away from the orifice.
15. The method of delivering mold charges from a receptacle containing a body of molten glass and provided with a submerged flow orifice, which consists in accumulating a quota of glass of determined size from the body of the glass, simultaneously moving the accumulating quota through the body and away from the orifice, in moving the quota through the body toward the orifice, in segregating the quota from the body and in delivering glass from the quota through the orifice without subjecting the quota to variations in fluid pressure.
16. The method of delivering mold charges from a receptacle containing a body of molten glass and having a flow orifice formed therein, which consists in accumulating and segregating a determined quota of glass from the body at a point adjacent the orifice, and in simultaneously reducing the pressure of the glass over the flow orifice, then in controlling the flow from the quota through the orifice by mechanically depressing or elevating the surface of the quota whereby a diaphragm-like action is obtained.
17. In combination with a receptacle adapted to contain a body of molten glass and having a flow orifice formed therein, means extending into the body of glass and movable from and toward the orifice to accumulate a quota of glass from the body, and means adapted to extend into the segregated quota and movable toward and away from the orifice to control the flow therefrom.
18. In combination with a receptacle adapted to contain a body of molten glass and having a flow orifice formed therein, variably movable means extending into the glass contained in the receptacle and movable from and toward the orifice to accumulate and segregate a quota of glass from the body of glass and variably movable means associated with said first-mentioned means and extending into the segregated quota and movable toward and away from the orifice to control the flow therefrom.
19. In combination with a receptacle adapted to contain a body of molten glass and having a flow orifice formed in the bottom thereof, a charge-accumulating element extending into the glass within the receptacle and open at its lower end, a member extending through said element and into the glass within the receptacle, means for moving said element and said member relatively to each other and away from the orifice to accumulate a charge of molten glass and toward the orifice to segregate the charge and control its delivery through the orifice.
20. The method of controlling the flow of molten glass from a mass of molten glass located above a submerged flow orifice, which consists in assisting the accumulation of a quota of molten glass within a sleeve, projecting into said mass to a point immediately above the flow orifice, by the upward movement of a punty-like member extending freely into the sleeve, and controlling the flow of molten glass from the quota through the orifice by moving the member so that its lower end projects beyond the lower end of the sleeve.
21. The method of controlling the flow of molten glass from a mass of molten glass located above a submerged flow orifice, which consists in assisting the accumulation of a quota of molten glass within the lower end of a sleeve, which projects into the mass to a point immediately above the flow orifice, by the upward movement of a punty-like member which extends into the sleeve, and then controlling the flow of molten glass from the quota through the orifice by moving the lower end of said member downwardly and into said orifice.
- In testimony whereof, I affix my signature.
- CARL H. RANKIN.
